SHOE HEEL

Filed Aug. 6, 1931

Inventor
Philip F. Havey,

Philip F. Havey

Attorney

UNITED STATES PATENT OFFICE

PHILIP F. HAVEY, OF WASHINGTON, DISTRICT OF COLUMBIA

SHOE HEEL

Application filed August 6, 1931. Serial No. 555,604.

The invention relates to the heel of shoes and analogous foot gear, whereby to absorb and prevent shock and cushion any tendency to jar when the wearer is walking, running or in action.

The invention contemplates a shoe having an opening extending through the heel and sole thereof and enlarged at its lower end, a soft rubber insert filling the opening and enlargement thereof, a metal strip molded in the insert and having its projecting ends overlying the sole and tacked thereto, a pad within the heel portion of the shoe overlying the sole and cemented thereto, said pad having an enlargement on its bottom side fitting a recess of corresponding shape formed in the top of the rubber insert and a cushion of sponge rubber placed upon the pad, the several parts being cemented or made secure in any determinate way.

The invention furthermore has as an object the provision of a shoe heel in which the rubber insert has molded therein a metal plate provided with spurs which project to prevent slipping which is desirable in shoes for athletes and those engaged in outdoor sports and games.

For a full understanding of the invention and the merits thereof, references is to be had to the drawings hereto attached and the subjoined description, in which corresponding parts are designated in the several views of the drawings and referred to in the specification by like reference characters.

In the drawings:-

Figure 1 is a fragmentary view in central longitudinal section of the heel portion of a shoe illustrative of an embodiment of the invention.

Fig. 2 is a bottom view of the parts shown in Fig. 1 on a reduced scale.

Fig. 3 is a horizontal section through the heel portion just above the sole.

Fig. 4 is a detail perspective view of the soft rubber insert and metal strip molded therein.

Fig. 5 is a detail perspective view of the pad which overlies the heel portion of the sole.

Fig. 6 is a detail sectional view of the soft

rubber insert having a metal plate provided with spurs embedded or molded therein.

Fig. 7 is a bottom plan view of the metal plate provided with spurs.

The shoe illustrated is of conventional structure and comprises an upper 1, an outer sole 2, and a heel 3 formed of a plurality of leather lifts. In accordance with the invention an opening is formed centrally through the heel 3 and extends through the heel portion of the sole 2.

This opening is enlarged at its lower end. A soft rubber insert is snugly fitted within the opening formed in the sole and heel of the shoe and the enlargement thereof and comprises a body portion 4 and an enlarged or head portion 5. This insert conforms to the opening formed in the sole and heel of the shoe and preferably is a trifle larger than said opening so as to be forced therein by pressure, thereby insuring a close and snug fit. It is obvious that cement may be applied to the insert to insure a water-tight joint between the heel and insert when the latter is in position. The application of cement to the insert also assists materially in retaining the insert in position against any casual displacement. A recess 6 is formed in the top or upper end of the insert and is adapted to receive a depending portion 7 of a pad 8 placed upon the heel portion of the sole 2.

A metal strip 9 has its middle portion deflected and embedded or molded in the body portion 4 of the insert. End portions of the strip 9 project and overlap the sole 2 adjacent the opening and are tacked to the sole, as indicated at 10. An anchoring pin 11 is molded in the insert and engages the metal strip 9 at the angle formed between the diverging portions, thereby assisting materially in securing the metal strip and preventing its withdrawal from the insert.

The pad 8 is of soft rubber and of a size to snugly fit within the heel portion of the shoe and overlie the sole 2. The forward end of the pad 8 is tapered to a feather edge to prevent any appreciable projection at the juncture of the pad with the sole 2.

The pad 8 is formed with an enlargement

7 upon its bottom side which is adapted to snugly fit within the recess 6 formed in the top of the rubber insert. A cushion 11^a of sponge rubber overlies the pad 8 and its forward end tapers and merges into the sole 2 to obviate the formation of any pronounced projection which would tend to cause discomfort.

When adapting the invention for shoes of 10 athletes and those engaged in outdoor sports and games, a metal plate 12 is molded or embedded in the lower or head portion 5 of the rubber insert. This plate is provided with spurs 13 which project so as to engage the 15 surface and prevent slipping. The spurs 13 may be welded or secured to the plate 12 in any preferred way. Projections 14 are provided on a side of the plate 12 and assist materially in retaining the plate in predetermined 20 position. These projections 14 may be formed by punching the plate 12 or partly cutting portions therefrom and bending said portions so as to project from a side of the plate to engage the rubber in which the plate is embedded.

It is observed that the rubber insert is disposed centrally of the shoe heel, hence, occupies a position in line with the calcaneum or heel bone of the foot so as to effectively 30 cushion the shock and jar incident to walking, running and other action. The head portion 5 of the rubber insert may extend across the bottom side of the shoe heel or terminate at any point from the sides thereof. In practice the insert will project slightly below the bottom side of the shoe heel and will be roughened, as indicated at 15 in Fig. 2, in any manner to prevent slipping.

If desired, the plate 12 may have apertures 40 16 therein to permit the passage of nails or other suitable fastenings (not shown), whereby to assist in securing the plate 12 against displacement.

What is claimed is:—

45 1. A shoe having an opening extending through its heel and sole, a rubber insert having a recess formed in its upper surface filling and secured within said opening, and a pad within the heel portion of the shoe and 50 having a depending portion engaging the opening in the sole and fitting the recess formed in the top of the insert.

55 2. A shoe having an opening extending through its sole and heel, a soft rubber insert snugly fitting within the opening, and a metal strap embedded or molded in the insert and having its end portions projecting and overlying the sole and tacked thereto.

60 3. A shoe having an opening formed in its heel and sole, a soft rubber insert fitted within the opening, a metal strap having its middle portion deflected and embedded in the insert and having its end portions projecting and overlying the sole and tacked thereto, 65 and an anchor embedded in the insert and en-

gaging the metal strap at the angle formed between the diverging portions of the deflected part.

4. A shoe having an opening extending through its heel and sole, a soft rubber insert 70 filling and secured within said opening and having a depression in its top, a pad disposed within the heel portion of the shoe and overlying the sole thereof and formed with a depending portion fitting the depression in the 75 top of the insert, and a cushion overlying the pad.

In testimony whereof I have hereunto set my hand this 6 day of August, 1931.
